(57) **CLAIM**

I claim the ornamental design for the bottle opener bracket, as shown and described.

DESCRIPTION

FIG. 1 is a perspective view of the bottle opener bracket, which illustrates the two different bottle openers and the light retaining clip of the bottle opener bracket;

FIG. 2 is a top view of the bottle opener bracket of FIG. 1; FIG. 3 is a bottom view of the bottle opener bracket of FIG. 1;

FIG. 4 is a side view of the bottle opener bracket of FIG. 1; FIG. 5 is a side view of the bottle opener bracket of FIG. 1, which illustrates the side opposite that shown in FIG. 4; FIG. 6 is a rear view of the bottle opener bracket of FIG. 1; and,

FIG. 7 is a front view of the bottle opener bracket of FIG. 1.
